UNITED STATES PATENT OFFICE.

CHARLES E. WAREAM, OF CINCINNATI, AND DANA H. BENJAMIN, OF CLEVELAND, HEIGHTS, OHIO, ASSIGNORS TO THE AMERICAN LAUNDRY MACHINERY COMPANY, OF CINCINNATI, OHIO, A CORPORATION OF OHIO.

NECKBAND FORMER.

Original application filed July 2, 1917, Serial No. 178,286. Divided and this application filed July 22, 1921. Serial No. 486,778.

To all whom it may concern:

Be it known that we, CHARLES E. WAREAM and DANA H. BENJAMIN, citizens of the United States, and residing at Cincinnati, 5 Hamilton County, Ohio, and Cleveland Heights, Cuyahoga County, Ohio, respectively, have invented certain new and useful Improvements in Neckband Formers, of which the following is a specification.

10 This invention relates to improvements in neckband formers for use in connection with ironing machines and the like.

This application is a division of our pending application Serial No. 178,286, 15 filed July 2, 1917.

The objects of this invention are to provide an improved neckband former together with a neckband clamp or clip for securing the front of a neckband of a shirt; to provide an extensible neckband former and a neckband clamp that is movably mounted upon the neckband former; and to so construct and arrange the neckband former that it will have yielding movement in a 25 direction normal to the main plane of the neckband former.

Other objects of this invention will appear from the following description and claims when considered together with the 30 accompanying drawings.

Fig. 1 is a plan view of our improved device; Fig. 2 is a section taken on line 2—2 of Fig. 1; Fig. 3 is a section taken on line 3—3 of Fig. 1; and Fig. 4 is a section taken on 35 line 4—4 of Fig. 1.

The padded ironing board 1 may be supported in any suitable manner. A longitudinal bar 2 lies in a recess of the board 1 beneath the padding thereon and is provided with a recess to receive the vertical pins 3 on which are located the sleeves 4 mounted in recesses in the stationary forward portion 5 of the neckband former. The sleeves 4 can rise and fall on the pins 40

45 3 with the ironing motion of the presser head or sad iron or the like, so as to allow the neckband former to sink with the padding when ironing pressure is applied to the shirt, but prevents any horizontal motion 50 of the stationary member 5 of the neckband former relative to the main support of the ironing board.

Suitable means is provided for enabling

the size of the neckband former to be varied to accommodate shirts of various sizes and to also enable the neckband former to be expanded in the neckband of the shirt and to produce the proper form thereof. The expanding movement is secured by moving back the back portions of the neckband former, but it is understood that since the curve of the neckband former always bears a definite relation to the folding line at the yoke end of the shirt board, the board is moved back with the back portions of the neckband former, although the mechanism for this arrangement is not here illustrated. This arrangement maintains the folding line at the neckband end of the shirt substantially tangent to the curve at the back 70 of the neckband in all sizes to which the neckband former is adjusted.

At one end the ironing board 1 carries the back yoke receiving frame 6 from which rises a plate 7 having a head 8 provided with a recess to receive a transversely extending rod 9 whose ends enter openings in the adjustable back portions 10 of the neckband former. Said back portions are attached to pins or rods 11 which enter horizontal 80 openings in the stationary forward portion of the neckband former, said openings diverging from the tail toward the neckband end of the shirt board as indicated in Fig. 1. When the shirt board 1 is moved rearwardly, the rod 9 is carried back and moves with it the adjustable rear portions 10 of the neckband former, said portions also moving outwardly from the full line to the dotted line position, Fig. 1, thereby 85 expanding the neckband former but substantially maintaining its neckband shape. The back yoke receiving member may be heated in any suitable manner, such as by electric current supplied to an electric unit 90 therein, as in the parent application before referred to.

The neckband of the shirt is applied to the neckband former unbuttoned, its edges merely meeting or abutting, although they may lap slightly if desired. The absence of buttons requires the meeting ends of the shirt neckband to be clamped or held against the stationary front portion of the neckband former before expanding the 100 former in the neckband to avoid separating

the meeting ends of the neckband. For this purpose we provide the neckband clamping member 15 which comprises the body portion 16 sliding in a recess in the top of the stationary portion of the neckband former and having a depending flange 17 lying in front of said former and whose inner surface next to the neckband may be padded or otherwise provided with a yielding clamp-
10 ing surface 18.

This clamping device is either rigidly or pivotally attached to the rod 19 around which is a spiral compression spring 20 tending to move said clamping member away
15 from the neckband former, that is to the release position. Rod 19 extends rearwardly through an opening in an L-shaped locking member 21 and then through an opening in the upwardly extending portion 22 of a slide
20 23 movable longitudinally in the stationary body portion of the neckband former and provided with a recess 24 to receive the lower edge of the locking member 21. A light compression spring 25 is located between
25 members 21 and 22 and tends to move the member 21 forwardly or to the right as viewed in the figures of the drawing. The opening in said member is slightly larger than the rod 19, so that when the vertical
30 portion of the member 21 assumes a position askew to the axis of rod 19 under the influence of spring 25, it grips the rod and prevents it from moving forwardly. Pressure applied by the fingers to the clamping
35 member 16 to push the same backwardly will swing member 21 backwardly about its lower edge, release the rod, and allow it to move rearwardly. This arrangement enables the shirt to be pressed upon the board
40 with the neckband surrounding the neckband former and the clamping member to be pushed backwardly by the fingers or thumb in light temporary clamping engagement with the neckband former. The slide
45 23 is also provided with a depending notched portion 26 to receive a forwardly extending toe 27 on the bar 28 which slides in a recess or channel of the bar 2, and whose forward end is suitably connected to operating
50 mechanism not here illustrated.

In preparing the shirt for ironing, it is placed upon the board with the ends of the neckband meeting or overlapping beneath the clamping member 17 which is pushed up
55 into clamping engagement with the neckband. The stationary body portion of the neckband former is usually provided with an under-cut groove or channel to receive the neckband as seen in Fig. 2, and a clamp-
60 ing action of the neckband clamp forces the neckband into its seat in said channel. The operating mechanism is then manipulated with the result that the bar 28 is moved to the left, as viewed in the drawings, and
65 likewise the slide 23 is also moved to the

left so as to cause the clamping member to be moved in the same direction into firm clamping engagement with the neckband. This operation and movement of the parts in the manner described is made possible by the engagement of the lower edge portion of the L-shaped locking member 21 in the notch in the upper part of the slide 23 and the binding or locking engagement of the locking member with the rod 19. Any suitable means may be adopted for operation of the slide 23 and the board 1 carrying the back yoke ironing portion. After the clamp has been brought into firm clamping engagement with the front portion of the neckband former, further manipulation of the operating mechanism affects the expansion or extension of the rear portions of the neckband former so as to take on the size and shape of the neckband of the particular shirt to be ironed. The shirt is then ready to be ironed either by hand or machine.

When the shirt has been ironed, it is released from the board by causing the rear portions of the neckband former to be moved inwardly so as to release the neckband of the shirt and the clamping member is released from engagement with the neckband so that the shirt can be readily removed. The clamping member is released by downward pressure by the operator upon the L-shaped locking member against the tension of the spring 25, whereupon the rod 19 is released from the binding engagement of the locking member and is at once moved to the right toward released position under the influence of the spring 20.

Whether the ironing operation is performed by means of an overhead steam chest as part of an ironing machine or by a manually operated sad iron, our improved device possesses the advantage which resides in the fact that no tearing of the neckband away from the body of the shirt will be caused by any ironing pressure at this point since the neckband former will yield to any such pressure. At the same time the neckband is held firmly clamped and is not disturbed by the yielding of the neckband former. Such an arrangement means a decided saving in cost of operation since it minimizes the loss by damage to the shirts being ironed.

What we claim is:

1. In a device of the character described, a neckband former, a neckband clamp movably mounted upon the front of said former, means for locking said clamp in clamping position, and means for tightening said clamp against said former while maintaining said clamp against release.
2. In a device of the character described, a neckband former, a neckband clamping means for operative engagement with the front of said former, means tending to nor-

mally force said clamping means to release position, a releasable lock for said clamping means, and means tending to normally force said lock into locking engagement with 5 said clamping means.

3. In a device of the character described, a neckband clamping means for operative engagement with the front of said former, a releasable lock for said clamping means, and 10 means co-operating with said lock for tightening the clamping engagement of said clamping means.

4. In a device of the character described, a neckband former, a slidable neckband 15 clamping means for operative engagement with the front of said former, a slidable member having operative connection with said clamping means for clamping the same, means for operating said slidable member, 20 and a releasable locking member operatively associated with said slidable member and

clamping means to tighten said clamping means upon operation of said slidable member and to lock said clamping means in engagement with said neckband former. 25

5. In a device of the character described, a neckband former, a slidable neckband clamp for operative engagement with the front of said former, a lock member, a rod connected at one end to said clamp and extending through said lock member, means 30 tending to normally force said lock member into locking engagement with said rod so as to prevent release of said clamp, a slidable means having operative connection with said lock member so as to cause sliding movement of said clamp into tight clamping engagement. 35

In testimony whereof we hereby affix our signatures.

CHARLES E. WAREAM.
